UNITED STATES PATENT OFFICE.

WARREN McARTHUR, JR., OF CHICAGO, ILLINOIS.

DESIGN FOR A TUBULAR-LANTERN FRAME.

45,266.

Specification for Design.

Patented Feb. 17, 1914.

Application filed November 22, 1913. Serial No. 802,553. Term of patent 14 years.

To all whom it may concern:

Be it known that I, WARREN McARTHUR, Jr., a citizen of the United States, residing at Chicago, in the county of Cook and State of Illinois, have invented a new, original, and ornamental Design for a Tubular-Lantern Frame, of which the following is a specification.

The accompanying drawing represents an elevation of a tubular lantern frame embodying this design.

The characteristic feature of this design consists of a base portion A of a tubular

lantern frame which has an arched or convex top B, and tubes C which rise from this convex top and which stand with their lower portions approximately perpendicular to the slope of the convex top B of the base portion of the frame.

I claim:

The ornamental design for a tubular lantern frame as shown and described.

WARREN McARTHUR, JR.
